United States Patent Office

Des. 179,483
Patented Jan. 1, 1957

179,483

TEXTILE FABRIC

Arnold G. Kovler, Fair Lawn, N. J., assignor to Chicopee Mills, Inc., a corporation of New York

Application September 5, 1956, Serial No. 42,839

Term of patent 14 years

(Cl. D92—1)

The figure is a plan view of a textile fabric showing my new design.

I claim:

The ornamental design for a textile fabric, as shown.
